UNITED STATES PATENT OFFICE

171,044

HORN RING EXTENSION

Ralph J. Morgan, Youngstown, Ohio

Application January 13, 1953, Serial No. 23,119

Term of patent 3½ years

(Cl. D14—6)

To all whom it may concern:

Be it known that I, Ralph J. Morgan, a citizen of the United States, residing at Youngstown, in the county of Mahoning and State of Ohio, have invented a new, original, and ornamental Design for a Horn Ring Extension, of which the following is a specification, reference being had to the accompanying drawing, forming a part thereof.

Figure 1 is a side elevation of a horn ring extension, showing my new design;

Figure 2 is a top plan view;

Figure 3 is a left end view;

Figure 4 is a right end view.

I claim:

The ornamental design for a horn ring extension, as shown.

RALPH J. MORGAN.
